UNITED STATES PATENT OFFICE.

FREDERICK HYMANS, OF GLEN RIDGE, NEW JERSEY.

BELL-HOIST.

1,309,632.

Specification of Letters Patent. Patented July 15, 1919.

Application filed December 14, 1917. Serial No. 207,044.

To all whom it may concern:

Be it known that I, FREDERICK HYMANS, a citizen of the Netherlands, residing in Glen Ridge, in the county of Essex and State of New Jersey, have invented a new and useful Improvement in Bell-Hoists, of which the following is a specification.

My invention relates to bell hoisting mechanism for use in connection with blast furnaces. An object of this invention is to provide an apparatus of the above-noted character involving certain improved features of construction such as will materially reduce the duty imposed on the hoisting mechanism, permitting the use of a comparatively light, high speed hoisting machine, and correspondingly light hoisting cable and other various parts involved in the opening and closing of the bell. A further object is the provision of means to automatically prevent excessive strains on the bell apparatus and hoisting mechanism, when in the closing of the bell, lumps of ore or other material become caught between the bell and its seat. Other objects of my invention will appear hereinafter.

In the accompanying drawings, Figure 1 shows a type of bell hoisting apparatus now used, and upon which my invention is an improvement. Fig. 2 shows a preferred form of my invention, and Figs. 3 and 4 are modifications of my improved apparatus shown in Fig. 2. Fig. 5 is a wiring diagram of the circuits for electrical apparatus which enters into the invention. Similar characters of reference indicate like parts throughout the several figures.

Referring to Fig. 1, I show a conventional type of furnace top 1, with a hopper 2, for receiving a charge of limestone, ore, coke, or other material, and what is known as the large bell 3, seated in the furnace top. The bell is connected by rod, 4, to one of a lever, 5, which lever is mounted on a beam 6 at pivotal support 7, and carries at its opposite end a weight 8 of sufficient mass to counterbalance the weight of the rod 4 and bell 3, plus the weight of the load of material resting thereon, the latter being not shown in the drawing, and to provide in addition a sufficient force to close the bell against the resistance offered by the mate-

rial in the hopper 2, and to maintain a heavy sealing pressure to hold the bell tight in its seat. The hoisting machine 9 comprises a double throw crank 10, rotated by a motor 11 through a train of gears 12. A brake 13 is provided to hold the bell in an open position. The crank is connected with a hoisting cable 14 which leads over a stationary sheave 15 to a hitch 16 on the lever 5.

In the apparatus described, since the stroke of the crank is necessarily limited, and since only one half a revolution of the crank is available for use, it will be seen that to obtain a sufficiently large movement of the bell the hitch 16 must be situated comparatively close to the fulcrum of the lever 5. As a consequence the stress imposed on the hoisting cable in operating the bell is very great, and the hoisting machine used must be of heavy construction with respect to gears, shafts and bearings, and therefore expensive. Moreover, since the distance of movement of the crank is so limited its circumferential speed in the hoisting operation must be low, requiring a large ratio of gearing between the driving motor and the crank, necessitating an expensive multiplication of parts. A further disadvantage of this apparatus is that when in the closing of the bell, lumps of material become caught between the bell and its seat the hoisting machine will continue to operate, causing the cable 14 to become slack. Then if the obstruction becomes suddenly dislodged, weight 8 will drop through a distance commensurate with the size of the obstruction, causing the bell to slam against its seat and causing excessive shocks and strains on all parts of the mechanism involved.

In Fig. 2, I show a preferred construction of my invention in which all of the disadvantages of the apparatus pointed out in Fig. 1 are overcome. Similarly as in Fig. 1, I show a furnace top 1, hopper 2, large bell 3, supporting rod 4 connected with one end of a lever 5, which is pivotally mounted on a beam 6 at support 7. At a point A preferably at the extreme opposite end of lever 5, I fix a sheave 17, and on the lever, between the sheave 17 and support 7, I place a relatively small counterweight 18 sufficient in mass to counterbalance with the aid of the

weights of sheave 17, only a part of the weight of the bell, bell rod, and lever, so that in the absence of other forces acting on the lever, the bell will open. It will be 5 obvious that the weight 18 may be dispensed with if desired. One end of a hoisting cable 19 is hitched to the lever 5 at point A, passing thence down under a sheave 20, mounted on a weight 21, which I shall call the sealing weight, since its function is to hold the bell sealed against its seat. The travel of weight 21 in a downward direction is limited by an abutment 22. The hoisting cable passes thence up over sheave 17 and down to 10 a hitch on a hoisting drum 23 of a hoisting machine 24. The latter in its preferred form comprises a motor 25 which drives the hoisting drum 23 through a worm gearing means 26. Spur gearing may be used if desired. 15 20 I provide an electromagnetically released brake 27 to hold the drum stationary, when the motor is not running. A cable 28 is hitched to the opposite side of the drum and passes up over a sheave 29 to a counterweight 25 30 of a mass sufficient to equalize the duty of the hoisting machine in lowering and raising the bell. Electrical contacts 31 operated by the weight 21 are so arranged that when the latter has been raised a given distance pref- 35 erably quite small, above abutment 22, the circuits for the motor and brake will be opened, causing the weight to remain, when hoisted, at a fixed distance above the abutment. Cams 32 and 33, rotated by the hoist- 40 35 40 ing machine, are arranged to actuate electric switches 34 and 35 respectively for automatically stopping the motor and applying the brake when the bell has been opened a predetermined distance, and for controlling the speed of the motor in a manner hereinafter described.

The operation of the apparatus shown in Fig. 2 is as follows: To lower the bell 3, the hoisting drum 23 is rotated in the direction indicated by the arrow with the result that the sealing weight 21 is lowered until it rests on the abutment 22. This removes the effect of the sealing weight and further rotation of the drum will permit the bell to open, 45 since as explained before, the weight of the bell is not altogether compensated for by the weights on the opposite side of lever 5. To close the now opened bell the direction of rotation of the hoisting drum is reversed. 50 55 The bell will be gradually closed, and after it is brought up against its seat the further rotation of the drum will cause weight 21 to be lifted off the abutment 22, thus again establishing the sealing pressure. The operation of motor 25 and brake 27 is controlled by manual and automatic apparatus shown diagrammatically in Fig. 5, the rotation of the motor in both directions being 60 65 automatically stopped at predetermined points, and the speed of the same being auto-

matically decreased at the time of the seating of the bell and of the movement of weight 21. I show here one system of wiring for accomplishing the desired results by the use of a direct current motor. Obviously any other type of motor might be used for the same purpose in connection with a suitable system of wiring. In Fig. 5, a manual double-throw operating switch 36 occupies the position shown to effect a closing of the bell, and is thrown over to effect an opening of the same. Reversing switches 37 and 38 complete circuits for the motor and brake to effect an opening and closing of the bell, respectively. An accelerating switch 39 is connected in a well-known manner across the motor armature 25' for the purpose of stepping out the starting resistance 40. A fast and slow speed switch 41 is arranged to introduce the resistance 42 into series with the motor field 25'' for increasing the speed of the motor, and to cut out the said resistance to decrease the motor speed. The switches 34 and 35 are actuated by the cams 32 and 33 respectively, 70 75 80 85 90 95 which are rotated by the hoisting machine in the direction indicated by the arrows in the operation of the opening of the bell. Contacts 31 are so arranged in connection with the weight 21 that the electrical contact is made while the weight occupies any position below a fixed point, at which point after the weight has been raised off the abutment 22, the contact is broken. The apparatus is here shown in the position occupied when the bell is closed and at rest. To open the bell, the operating switch 36 is thrown over completing a circuit for the reversing switch 37 from the plus main, conductor 43, magnet of switch 37, conductor 44, switch 34, 100 105 110 conductor 45, switch 36, conductor 46 to the minus main. The operation of switch 37 closes circuits for the motor armature 25', motor field 25'', and for the magnet of brake 27, which operate as already described to open the bell. Since the resistance 42 is short circuited through switch 41, the motor starts at low speed, lowering the weight 21 onto its abutment and making without effect a connection at contacts 31. 115 120 125 Cams 32 and 33 rotate simultaneously in the direction indicated by the arrows. Shortly after the weight 21 rests on its abutment, the cam 33 engages the arm of switch 35 closing the contacts thereof and completing a circuit for the switch 41, from the plus main, contacts 47, conductor 48, switch 35, conductor 49, magnet of switch 41, conductor 50, conductor 46 to the minus main. The operation of switch 41 inserts the resistance 125 42 into series with the motor field 25'' causing the motor to rotate at high speed for the remainder of the bell opening operation. When cam 32 engages switch 34, the contacts of the latter are opened, interrupting 130

the circuit for reversing switch 37 causing the said switch to open, stopping the motor and applying the brake. The bell is now opened with the weight 21 resting on its abutment and the connection made at contacts 31. Now to close the bell, the operating switch is thrown over into the position shown in the drawing, completing a circuit for reversing switch 38 from the plus main, conductor 43, magnet of switch 38, conductor 51, contacts 31, conductor 52, switch 36, conductor 46 to the minus main. The operation of switch 38 completes circuits for the motor armature 25', motor field 25'', and magnet of brake 27, which operate as already described to close the bell and seal the same in its seat by raising the weight 21. The switch 35, being in a closed position completes a circuit for switch 41 from the plus main, contacts 53, conductor 48 and thence as previously traced, causing switch 41 to operate to insert the resistance 42 into series with the motor field 25'', so allowing the bell closing operation to start at high speed. The rotation of cams 32 and 33 in the direction opposite to that indicated by the arrows causes the closing of switch 34 without effect, and shortly before the bell is seated causes the opening of switch 35, interrupting the circuit for switch 41, causing the latter to close and short circuit the field resistance 42, causing the motor to operate at low speed at the time of the seating of the bell and the subsequent raising of weight 21. When the latter has been raised a predetermined distance, the contacts 31 are opened, interrupting the circuit for the magnet of switch 38, causing the latter to open, so stopping the motor and applying the brake.

It will be seen that if in the closing of the bell, lumps of material become caught between the bell and its seat, so preventing a closure, no shocks or strains on any part of the apparatus can result. When such an obstruction halts the movement of the bell, the continued rotation of the hoisting drum will cause weight 21 to be lifted off the abutment 22 similarly as if no such obstruction had interrupted the operation. Now, if the obstruction becomes suddenly dislodged, the weight 21 will drop onto the abutment 22, and the bell will be raised through a small distance commensurate with the drop of weight 21, regardless of the size of the obstruction, and at a rate of speed less than that of weight 21. In practice such a dropping of weight 21 would not be sufficient to cause a closing of the bell, but would serve merely to complete the motor circuits on account of the closing of contacts 31, and cause a closing of the bell and re-raising of the weight 21, similarly as in normal operation.

In Fig. 2, the bell is shown closed and held

sealed against its seat by the force of weight 21, which is held suspended by the action of brake 27. It will be seen that the downwardly directed force P , required at point A to hold the bell seated, is distributed equally over the three leads extending downward from that point, one lead from the hitch, and two leads from the sheave 17. Thus the stress on the hoisting cable in raising the weight 21 is equal to only $\frac{P}{3}$. Also since two leads extend upward from the weight 21, the mass thereof need be only $\frac{2P}{3}$. If the weight 21 were directly attached at the point A its mass would necessarily have to be equal to P and the stress on the hoisting cable in lifting the weight would likewise be equal to P , whereas with the arrangement shown the same effect in producing the force P at point A is accomplished by using a weight 21 of a mass of $\frac{2P}{3}$, and with a stress on the hoisting cable of no more than $\frac{P}{3}$. It will be seen that in Fig. 2, the weight 21 travels at one half, and point A at one third of circumferential speed of the hoisting drum. Thus for a given speed of movement of the bell the speed of the drum will have to be relatively high, permitting the use of a cheap, high speed motor without requiring a great ratio of gearing between the motor and drum. In the crank type of machine shown in Fig. 1, in order to obtain the same results that I accomplish in my invention, the weight 8 must be of a mass equal to P , and owing to the limited stroke of the crank, the hoisting cable must be hitched to the lever 5 at a point considerably closer to the fulcrum than the point where the weight is suspended, with a resultant stress on the hoisting cable several times as great as P .

In view of the foregoing facts and comparisons, it is evident that in my invention I can employ a hoisting apparatus much smaller and lighter in the construction of all its parts than that hoisting apparatus required in the mechanism shown in Fig. 1.

In the modifications shown in Figs. 3 and 4, the construction and operation is identical as described for Fig. 2 with the exception of the arrangement of the hoisting cables and of the masses of the sealing weights. In Fig. 3 the end of cable 19' is hitched to the weight 21' thence passing up over sheave 17 and down to a hitch on the drum 23. In Fig. 4 an additional sheave 54 is provided on the lever 5 at the point A. One end of the cable 19'' is hitched to the weight 21'', passing thence up over sheave 54, down under sheave 20, up over sheave 17, and down to a hitch on the drum 23.

Referring to Fig. 3, in order to produce the required downwardly directed force P at point A, weight 21' need have a mass of only $\frac{P}{2}$ while the stress on the cable 19' will

be equal to $\frac{P}{2}$. The weight 21 will travel at the same speed and the point A at one half of the circumferential speed of the hoisting drum. Referring to Fig. 4, a downwardly directed force P is produced at point A by a weight 21'' of a mass equal to $\frac{3P}{4}$ and with a stress on the hoisting cable of $\frac{P}{4}$. The weight 21'' will travel at one third, and the point A at one fourth of the circumferential speed of the hoisting drum. Obviously any number of multi-leads in the hoisting cable may be used, the required mass of the sealing weight increasing, and the stress on the hoisting cable decreasing with increased number of leads. Also with such increased leads the rates of travel of the sealing weight and of point A will decrease accordingly. With any number, n , leads between the sealing weight and the point A, at which point a downwardly directed force P is required, the mass of the sealing weight will be equal to $\frac{n \times P}{n+1}$, and the stress on the hoisting cable will be equal to $\frac{P}{n+1}$. Also the sealing weight will move at $\frac{1}{n}$ and the point A at $\frac{1}{n+1}$ of the circumferential speed of the hoisting drum. In view of the necessarily increased size of the sealing weight with increased leads in the hoisting cable, I have selected the construction shown in Fig. 2 as the preferred form of my invention. In Figs. 2, 3, and 4 I have shown the sealing weights 21, 21', 21'' as sectional, and have assumed a required downwardly directed force P at point A, equal to the mass of twelve sections. Thus according to the formulæ previously given, the required number of sections in the respective sealing weights are eight, six and nine.

Obviously those skilled in the art may make various changes in the details, arrangement and construction of parts in such apparatus as described without departing from the spirit and scope of my invention. I desire therefore not to be limited to the exact constructions herein described.

I claim:

1. In bell hoisting apparatus, a bell and means to actuate the same comprising a lever supporting the bell, a sheave mounted on the lever, a sealing weight, a cable acting on the sheave and the weight, and means to actuate the cable.

2. In bell hoisting apparatus, a bell and means to actuate the same comprising a lever supporting the bell, a sealing weight, an abutment upon which the weight may rest, a cable acting on the lever and the weight, and means to actuate the cable.

3. In bell hoisting apparatus, a bell, and means to actuate the same, comprising a lever supporting the bell, a sealing weight, multiplying sheaves mounted on the lever and weight, a cable acting on the sheaves, and means to actuate the cable.

4. In bell hoisting apparatus, a bell, and means to actuate the same, comprising a lever supporting the bell, a sealing weight, an abutment on which the weight may rest, sheaves on the lever and the weight, a cable arranged with one end fast, and the other end led around and embracing the sheaves, and means to actuate the cable.

5. In a bell hoisting apparatus, the combination of means to open and close the bell, comprising a lever, one arm of which is adapted to suspend a sealing weight and the other arm the bell, a sealing weight, a drum, and a hoisting cable, one end of the cable being passed over the arm that carries the sealing weight and made fast to the latter, and the other end of the cable passed around the drum, and means to rotate the drum, to raise the weight to lift the bell to seat it and to lower the weight to lower the bell to unseat it.

6. In bell hoisting apparatus, a bell, a lever supporting the same, a sheave on the lever, a stationary sheave, a cable passing over the sheaves and acting on the lever, and weights on the cable and means to actuate the cable and weights.

7. In bell hoisting apparatus, a bell, a lever supporting the same, a cable acting on the lever, a hitch at one end of the cable fast to the lever and actuating means for the cable at the opposite end thereof and a sealing weight between the lever and the actuating means for the cable.

8. In bell hoisting apparatus, a self-opening bell, a seat therefor, a lever supporting the bell, and means to seal the bell against and to unseal the same from its seat, comprising a weight, an abutment on which the weight may rest, and means to move the weight into and out of suspension from the lever, by moving the weight out of and into rest on the abutment.

9. In bell hoisting apparatus, a self-opening bell, a seat therefor, a lever supporting the bell, and means to seal the bell against, and to unseal the same from its seat, comprising a weight, an abutment on which the weight may rest, and means to move the weight into and out of suspension from the lever, comprising a cable connecting the weight with the lever, and means to actuate the cable.

10. In bell hoisting apparatus, a self-opening bell, a seat therefor, a lever supporting the bell, and means to seal the bell against, and to unseal the same from its seat comprising a sheave on the lever, a weight, a cable passing over the sheave and acting on the weight to move the latter into and out of suspension from the lever.
- 5 11. In bell hoisting apparatus, a self-opening bell, a seat therefor, a weight to hold the bell sealed against its seat, an abutment on which the weight may rest, a hoisting apparatus to move the weight and hold the same suspended off the abutment, and automatic means to halt the hoisting mechanism when the weight has been moved a predetermined distance off the abutment.
- 10 12. In bell hoisting apparatus, a self-opening bell, a seat therefor, a weight to hold the bell sealed against its seat, an abutment on which the weight may rest, an electric hoisting apparatus to move the weight and to hold the same suspended off the abutment, and electrical contacts controlled by the weight to cause a halting of the hoisting apparatus, when the weight has been moved a predetermined distance off the abutment.
- 15 13. In bell hoisting apparatus, a self-opening bell, a seat therefor, a weight to hold the bell sealed against its seat, an electric hoisting apparatus, including a resistance to vary the motor field to actuate the bell and the weight, and electrical contacts for cutting out the said resistance controlled by the hoisting apparatus to reduce the speed of the latter during the movement of the weight.
- 20 14. In bell hoisting apparatus, a self-opening bell, a seat therefor, an electric hoisting apparatus, including a resistance to vary the field of the motor to close the bell, and electrical contacts for cutting out the said resistance and controlled by the hoisting apparatus to reduce the speed of the latter when the bell is brought into contact with its seat.
- 25 15. In bell hoisting apparatus, a self-opening bell, a seat therefor, a weight to hold the bell sealed against its seat, an abutment on which the weight may rest, automatic means to lift the weight a predetermined distance off the abutment irrespective of obstructions between the bell and its seat, and automatic means to effect a closure of the bell when the obstructions become dislodged.
- 30 16. In bell hoisting apparatus, a self-opening bell, a seat therefor, a weight to hold the bell sealed against its seat, an abutment on which the weight may rest, automatic means to lift the weight a predetermined distance off the abutment irrespective of obstructions between the bell and its seat, and means controlled by the weight to automatically effect a closure of the bell when the obstructions become dislodged.
- 35 17. In bell hoisting apparatus, a self-opening bell, a seat therefor, a weight to hold the bell sealed against its seat, an abutment on which the weight may rest, an electric hoisting apparatus to actuate the bell, and to seal the bell against, and to unseal the same from its seat by raising and lowering the weight from and into engagement with the abutment, and electrical contacts constituting a switch to the hoisting motor controlled by the weight, to cause the latter to be raised a predetermined distance off the abutment irrespective of obstructions between the bell and its seat, and to cause a closure of the bell when the obstructions become dislodged.
- 40 18. In a bell hoisting apparatus, the combination of a lever, a sealing weight for the bell, suspended on one arm of the lever, and the bell on the other arm thereof, and a drum rotatable to lift the bell and the sealing weight, a hoisting cable on the drum and freely embracing the said arm adapted to move both relatively to and absolutely of the said lever and connect together the lever, the sealing weight and the drum, and upon rotation, to lift the bell and the sealing weight, and, in case of an obstruction preventing the lifting of the bell to close the same, the continued rotation of the drum will lift the sealing weight, and thereby avoid undue strain upon the apparatus.
- 45 In testimony whereof I have signed my name to this specification in the presence of two subscribing witnesses.
